CLAIM

The ornamental design for a backpack, as shown and described.

DESCRIPTION

FIG. 1 is a perspective view of a my backpack, showing my new design in a closed configuration;

FIG. 2 is a front elevational view of FIG. 1;

FIG. 3 is a rear elevational view of FIG. 1;

FIG. 4 is a left-side elevational view of FIG. 1;

FIG. 5 is a right-side elevational view of FIG. 1, FIG. 5 being a mirror-image of FIG. 4 but for the zipper pull;

FIG. 6 is a top plan view of FIG. 1;

FIG. 7 is a bottom plan view of FIG. 1;

FIG. 8 is a top perspective view thereof, illustrated in an open configuration;

FIG. 9 is a rear perspective view of FIG. 8; and,

FIG. 10 is a front perspective view of FIG. 8 but showing the backpack in a fully open configuration.

The dot-dash broken lines depict portions of the backpack that form no part of the claimed design. The long dash lines in FIGS. 8–10 illustrating a tablet depict environmental subject matter that forms no part of the claimed design. The heavy weight broken lines in FIGS. 8–10 represent the zipper closure and are part of the claimed design. The remaining broken lines depict stitching, and are part of the claimed design.
